UNITED STATES PATENT OFFICE.

EDWARD JANDREAU, OF CHERRY VALLEY, NEW YORK.

RAIL CHAIR AND BRACE.

No. 930,762.

Specification of Letters Patent.

Patented Aug. 10, 1909.

Application filed April 24, 1909. Serial No. 491,877.

To all whom it may concern:

Be it known that I, EDWARD JANDREAU, a citizen of the United States, and a resident of Cherry Valley, in the county of Otsego and State of New York, have invented a new and Improved Rail Chair and Brace, of which the following is a full, clear, and exact description.

This invention relates to rail chairs and braces for railway and like tracks, and relates more particularly to a device of this class comprising a chair plate adapted to carry the rail and having means for holding the rail, and a brace member mounted upon the chair and engaging the rail to hold it against lateral movement, the plate and the brace having an opening adapted to receive a common spike.

The object of the invention is to provide a simple, inexpensive and durable rail chair and brace, by means of which railroad rails can be securely held in place upon the cross ties, and which serve to brace the rails against lateral movement at curves and other points of the track where such bracing is necessary.

The invention consists in the construction and combination of parts to be more fully described hereinafter and particularly set forth in the claim.

Reference is to be had to the accompanying drawings forming a part of this specification, in which similar characters of reference indicate corresponding parts, and in which—

Figure 1 is a perspective view of an embodiment of my invention holding a rail, the latter being in cross section; Fig. 2 is a plan view of the device showing a part of a rail thereon; and Fig. 3 is a longitudinal section on the line 3—3 of Fig. 2.

Before proceeding to a more detailed explanation of my invention, it should be clearly understood that the same can be fashioned from any suitable material, but I preferably employ for this purpose, cast metal. Ordinary rail spikes can be used in connection therewith as will appear more clearly hereinafter.

The device is reversible, that is, it can be used to brace either side of the rail, and at the same time serves to mount the rail securely upon the tie. It tends to prevent the wearing away of the tie owing to the binding of the rail, as it is difficult for the rail to work loose.

Referring more particularly to the drawings, I provide a chair or base plate 10 of elongated form and of sufficient width to provide a firm support for the rail, which extends transversely of the length of the plate. At one end, the plate has preferably integral holders 11 consisting of upwardly and rearwardly disposed claws adapted to receive underneath them one edge of the rail base 19, as is shown most clearly in Fig. 1, to hold the rail upon the chair. Between the holders 11, the plate has an extension 12 provided with an opening 13 therethrough adapted to receive a rail spike 14 which is driven into the tie 15 to hold both the rail and the plate in position.

Mounted upon the plate, at the side of the rail remote from the holders 11, is the bracing member 16 which has substantially the form of a wedge, and which at the broad end has a cut-away part 17 so that it can fit snugly upon the rail base 19. The broad end 18 of the brace 16 is so formed that it can fit evenly against the rail web 20, between the rail base 19 and the rail head 21, as is shown most clearly in Fig. 3.

The chair plate and the brace have respectively, openings 22 and 23 therethrough which are arranged to register when the brace is in position, and to receive a rail spike 24. The latter is driven into the tie 15 and serves to hold the plate and the brace in position and to secure the brace upon the plate.

Preferably, additional rail spikes 25 are driven into the tie at the opposite longitudinal edges of the chair plate and against the rail base 19 at the side of the rail near the brace 16. These additional spikes assist in preventing the displacement of the chair in the direction of the length of the rail, and also serve to hold the rail with respect to the tie.

Having thus described my invention, I claim as new, and desire to secure by Letters Patent—

1. A rail chair and brace, comprising a cast metal base plate having an opening adjacent to one end and provided at its other end with upwardly and rearwardly extending claws adapted to receive and fit snugly upon the base flange of the rail and between the claws with an extension having an opening in alignment with the claws and adapted to receive a spike to hold the rail and base plate in position, and a brace of even width

throughout and arranged centrally upon the base plate, said brace having one end constructed to fit upon the base flange of the rail and against the web of the rail and provided with an opening registering with the opening of the base plate and adapted to receive a spike to secure the base and brace to the tie.

In testimony whereof I have signed my name to this specification in the presence of two subscribing witnesses.

EDWARD JANDREAU.
